UNITED STATES PATENT OFFICE.

CHARLES HAMMER, OF NEW YORK, N. Y., ASSIGNOR TO AMERICAN METAL CAP COMPANY, OF BROOKLYN, NEW YORK, A CORPORATION OF NEW YORK.

CATSUP-CAP AND METHOD OF MAKING THE SAME.

1,178,153.

Specification of Letters Patent.

Patented Apr. 4, 1916.

Application filed May 16, 1914. Serial No. 839,128.

To all whom it may concern:

Be it known that I, CHARLES HAMMER, a citizen of the United States, residing at New York, in the county and State of New York, have invented certain new and useful Improvements in Catsup-Caps and Methods of Making the Same, of which the following is a specification.

This invention relates to closure members admitting of general use, and more particularly to bottle caps of a kind suitable for catsup bottles, in order to seal the same.

My invention further relates to a method for making the bottle caps.

Reference is made to the accompanying drawing, forming a part of this specification, and in which like letters indicate like parts.

Figure 1 is a plan view of a sheet metal blank used in forming the cylinder or body portion of the cap. Fig. 2 is a plan view of a disk used for closing one end of the cylinder. Fig. 3 is a perspective view of the blank as bent into cylindrical form and otherwise shaped as a part of the cap. Fig. 4 is a perspective showing the partially formed cap, including the body portion and the disk. Fig. 5 is a section on the line 5—5 of Fig. 3. Fig. 6 is a perspective of the finished cap. Fig. 7 is a section on the line 7—7 of Fig. 2, showing the disk.

A substantially rectangular strip of metal is shown at 8, and is provided at one of its ends with a tongue 9 integral with it; this tongue having substantially the form of a truncated triangle. The strip 8, including the tongue 9, is of such form that two such strips complete may readily be cut from a single longitudinal member of sheet material without undue waste. A disk 10, made also of sheet metal, is provided adjacent its edge with an annular bead 11. The disk is further provided with another annular bead 12, the latter being used merely for ornamentation. The strip 8 is bent into the proximate form of a cylinder, as shown at 8^a in Fig. 3, one end of the strip slightly overlapping the other, one edge of the cylinder being bent slightly inward as shown at 13, the opposite edge being bent slightly outward as indicated at 14. The disk 10 is placed within the cylindrical member 8^a and lodged against the inturned portion 13 thereof. The disk 10 and the inturned edge 13 of the strip are secured together by rolling or

crimping. The outwardly turned portion 14 is next bent or crimped upwardly according to Figs. 3 and 4, so as to form an annular bead 15, as may be understood from Fig. 4. A portion 16 of this annular bead 60 is merely an edge portion of the cylindrical member 8^a, but is bent over the adjacent edge portion of the tongue 9. This being done a number of indentations or impressions 17 are made in the edge of the portion 16, so 65 as to crimp or pitch this edge firmly in place so as to hold the member firmly in the proximate form of a cylinder. The indentations 17 may be made in various ways, as by peening, punching, or even by subjecting the 70 device to the pressure of the edge of a toothed wheel. At the same time this step is performed or at any subsequent time as desired, a spiral thread 18 is formed in the lower portion of the cylindrical member, the formation of this thread being simply the bending of the sheet metal into suitable shape for the purpose, as indicated in Fig. 6. The upper portion of the cylindrical member is provided with a number of ribs 19 disposed parallel with each other and collectively constituting practically a milled surface for enabling the operator to screw the cap on to a bottle or to remove the cap from said bottle. 85

I do not limit myself to the precise construction shown, as variations may be made therefrom without departing from the spirit of my invention.

Having thus described my invention, what 90 I claim as new and desire to secure by Letters Patent is:—

1. The method herein described of making bottle caps which consists in forming a strip of sheet material provided with a tongue extending from one end thereof, bending said strip of sheet material into the proximate form of a cylinder, so as to bring said tongue close against an adjacent edge portion of said strip, bending said edge portion of said strip over the adjacent edge portion of said tongue, crimping said edge portion and said tongue together, and securing a disk to one end of said cylinder. 95

2. The method herein described of making bottle caps, which consists in forming a strip of sheet material provided with a tongue integral therewith and having the proximate form of a truncated triangle, bending said strip into the proximate form 110

of a cylinder, bending one edge of said cylinder slightly inward, bending the opposite edge of said cylinder slightly outward, securing a disk to one end of said cylinder 5 in order to close the same and bending and clenching together one edge of said tongue and an adjacent edge of said cylinder overlapped by said tongue.

3. A bottle cap comprising a substantially 10 cylindrical member of sheet material having one of its edges formed into an annular bead so that a portion of said edge overlaps another portion thereof, and a disk closing one end of said cylindrical member.

15 4. A closure cap comprising a strip of sheet material bent into the proximate form of a cylinder and provided with overlapping ends, one of said ends being a tongue integral with it, said strip being provided with 20 an edge portion bent over the adjacent portion of said tongue and secured thereto by crimping, and a disk closing one end of said cylinder.

5. A bottle cap comprising a strip of sheet 25 material provided with overlapping ends and bent into the proximate form of a cylinder, said strip being provided with a tongue overlapping one of its ends, an edge portion of said tongue and the adjacent edge portion 30 of said strip being crimped together in order to hold said strip in the proximate form of a cylinder, and a disk closing one end of said cylinder.

6. A bottle cap comprising a strip of sheet 35 material, bent into the proximate form of a cylinder and provided with overlapping ends and with a tongue integrally connected with one end and overlapping the other end, the edge portion of said tongue being 40 slightly bent and overlapped by the adjacent edge portion of said strip in order to hold said strip in the proximate form of a cylinder, and a disk connected with the opposite edge portion of said cylinder, for the purpose 45 of closing said cylinder.

7. In a closure cap, a strip of sheet ma-

terial bent into the proximate form of a cylinder and provided with ends, one of which overlaps the other, said strip being further provided adjacent its ends with edge 50 portions, one of which overlaps the other and is crimped thereto.

8. In a closure cap, a strip of sheet material bent into the proximate form of a cylinder and provided with ends, one of 55 which overlaps the other, said strip being further provided adjacent its ends with edge portions, one of which overlaps another so as to hold said strip, and a disk connected with one edge of said cylinder for closing 60 said cylinder.

9. In a closure cap, the combination of a strip of sheet material provided with a tongue integral therewith, said strip being provided with ends and bent into the proximate form of a cylinder, so that one end overlaps the other and that said tongue overlaps another portion of said strip, one edge of said tongue and the adjacent edge of said strip overlapped thereby being bent 70 outwardly and crimped, said cylinder being provided adjacent one of its ends with a spirally disposed thread and a disk connected with the opposite end of said cylinder 75 for closing the same.

10. The method herein described of making bottle caps which consists in giving a strip of sheet metal the approximate form of a cylinder, and causing the ends of said strip to overlap, then turning over the edges 80 of the overlapping ends of said strip at one side thereof, and subjecting said turned over edges to pressure to secure them firmly together.

In testimony whereof, I have signed my 85 name to this specification in the presence of two subscribing witnesses, this 9th day of May, 1914.

CHARLES HAMMER.
